UNITED STATES PATENT OFFICE.

WILLIAM E. STUART, OF SAN FRANCISCO, CALIFORNIA.

COMPRESSED-AIR PUMP.

1,014,422.

Specification of Letters Patent. Patented Jan. 9, 1912.

Application filed January 5, 1911. Serial No. 600,926.

To all whom it may concern:

Be it known that I, WILLIAM E. STUART, a citizen of the United States, residing at San Francisco, in the county of San Francisco and State of California, have invented new and useful Improvements in Compressed-Air Pumps, of which the following is a specification.

The present invention relates to improvements in pumps operated by means of compressed air, the same being especially adapted for deep well pumps.

The object of my invention is to provide a pump of this character which will be efficient and economical in its action, and produce a regular flow of the liquid operated upon as oil or water, and which, can be used as either a pressure or a suction pump, thereby enabling a large number of wells 20 to be pumped from the central station.

In the accompanying drawings, Figure 1 is a side view of my invention applied to a deep well; Fig. 2 is an enlarged vertical section, partly in side elevation, of a portion of the well showing in section the compressed air ports and the valve for controlling the same; Fig. 3 is a similar view of the lower portion of the well showing in section the lowermost air ports; Fig. 4 is a vertical 30 section of the upper portion of my improved pump, the valve-controlling device being shown in side view; Fig. 5 is an enlarged vertical section of said valve-controlling device.

Referring to the drawings, 1 indicates a compressed air supply pipe, which enters the side of a cylinder 2. Through the head 3 at the top of said cylinder can slide a tube 4. Said tube is attached at its upper end 40 to a hollow piston 5, which slides within a main cylinder 6, said cylinder 6 being supported by standards 7 upon the top of a receptacle 8 supported by a suitable concrete structure 9 upon the surface of the ground around the well 10, in which receptacle 8 the liquid, such as oil, is received, and from which it flows by a discharge pipe 11. The compressed air from the pipe 1 enters the lower open end of said tube 4 and passes upward therein, discharging from which is adjusted by a pin valve 14, and then by a passage 15 into the space 16 within the hollow piston 5. In said hollow 55 piston is secured a regulating cylinder 17,

into the ends of which compressed air enters by two passages 18, 19, so that a piston 20 therein is balanced. Said piston 20 is formed with upper and lower heads 21, 22, spaced from each other, the body of the 60 piston being reduced in diameter, and therefore being spaced from the cylinder 17 to form a chamber 23. Into said chamber 23 the compressed air enters by a passage 24 through the cylinder 17, and from said 65 chamber it may escape either by a passage 25 into the lower portion of the main cylinder 6, or by a passage 26 into the upper portion thereof, said latter passage being adjusted by a pin valve 28. It cannot, however, escape into said upper passage from 70 said chamber 23 while said chamber 23 is in communication with the passage 24, but only when said chamber is only in communication with the lower passage 25. In the position shown in the drawing compressed air passes by the passage 24 into the chamber 23 and by the passage 25 into the lower portion of the cylinder 6 and the passage 26 is closed by the upper piston head 21. The 75 upper end of the cylinder 6 is open to the atmosphere by the passage 30. Therefore the compressed air presses the main piston 5 upwardly, until an arm of a lever 31, pivotally attached to a stem 32 of the said 80 piston, extending through the head 33 of the cylinder 17 impinges against a screw stop 34. When this occurs, the long arm of said lever 31 is moved upwardly, shifting the piston 20 to its upper position, and closing the passage 24 by the lower piston head 22, while at the same time causing the two 85 passages 25 and 26 to communicate with each other through the chamber 23. Compressed air then flows from the lower portion of said main cylinder 6 to the upper portion thereof and thence to the atmosphere by the passage 30. The main piston 5 thereupon owing to the weight of the parts depending therefrom, as hereinafter 90 described, descends on an air cushion controlled by the pin valve 28.

The downward movement of the piston is automatically reversed by a lever 41, the operation of which is similar to that of the 105 lever 31.

Supported upon a coiled spring 35 surrounding said tube 4 and resting upon a lower collar 36 on said tube, is a yoke 37, from which depends a tube 38, open at the 110

top, and passing through a stuffing box 39 in the lower end of the cylinder 2, and thence passing through the receptacle 8, and then centrally down the pump casing 40, which is contained within the oil well casing 10, said pump casing 40 being supported upon the concrete structure 9. Said tube is divided into sections 42, said sections having collars 43 thereon some of which are provided with suitable arms 44 maintaining it centrally within the tube 40. Said sections are movable vertically relative to each other, the lower end of each section being screwed, as shown at 45, to a piston valve 46, which slides within a valve casing 47, screwed, as shown at 50, to the upper end of the next lower section 42, said valve casing being secured to the upper portion of the next lower section by a set screw 94. Gaskets 51 are received within recesses of the valve casings to provide a tight fit to the valves 46 thereof.

The lowermost section 42 is rotatably connected to a socket 54, by being screwed therein, as shown at 53, which socket 54 in turn is screwed to a sleeve 55, and has formed integral therewith at its lower end a stem 56, which rests in a seat 57 supported by arms 58 from a sleeve 60 of the pump casing 40. Said stem 56 is provided with a lug 61 which engages a notch 62 of the seat to prevent the stem turning. In this position a lug 63 extending from the lower end of each section engages a recess 64 in the sleeve connected to the section next below it and compels the two sections, and in consequence all of said sections, to rotate together. When the sections move vertically with reference to one another, as hereinabove described, said lug also moves vertically in the groove or recess 64 formed therefor in the corresponding sleeve.

On first inserting the pump into a well, the lowermost section is screwed down within the socket 54 sufficiently far to close openings 70 through said socket, and each of the sections above the lowermost section assumes its lowermost position with regard to the section next below it, the piston valve 46 of each section resting upon the lower gasket 51 in the top of the next lowermost section. The result is that compressed air cannot then escape from within the tube sections by the openings 70, or by openings 71 in the bottom of each section above the lowermost, said openings 71 being at that time closed by being below the top of the next section below it. The first operation, therefore, is to open the apertures 70, which is done by screwing backward the whole of the tube sections, and thereby raising the lowermost tube section with reference to the socket 54, until the bottom of said tube section ascends above the openings 70 as shown in Fig. 3. When the bottom of the lower-

most section has been thus screwed above the apertures 70, compressed air, passed from the pipe 1 into the open top of the uppermost tube section, passes by said apertures 70 into a chamber 72 formed in the sleeve 55 and escapes from said chamber 72 by holes 73, 74, extending obliquely upward. While this is taking place, the piston 5 ascends, owing to the pressure of compressed air as before described. The ascent of the piston produces a corresponding ascent of the uppermost tube section, causing the piston valve 46 of said uppermost section to be raised from its seat and compressed air to escape by the apertures 71 to the space between said valve and seat, then by channels 75 to the space above the piston 46 and below the upper gasket 51, and then by channels 76 to apertures 77 extending into the discharge chamber of the pump 85 obliquely upward, and also by channels 78 into upper apertures 80 also extending obliquely upward. During this time compressed air is being discharged into the pump casing from the uppermost series of apertures as well as from the lowermost. When the piston valve 46 arrives at its uppermost position, the compressed air passages past said valve are closed, but immediately thereafter, by reason of the fact that the main piston 5 continues to ascend, the compressed air can now pass in like manner through the apertures 71 of the next lower section, around the piston valve 45 thereof, and out into the chamber in the same manner as before described. In this manner compressed air can be caused to pass from the bottom of each section in succession into the pump chamber. During the whole of this time the compressed air 105 is passing into the bottom of said chamber by the ports 70, 72, 73. By this means the liquid is caused to ascend in said pump and to be discharged into the receptacle 8 from which it is conducted by the pipe 11. 110 Liquid to supply its place flows upward between the arms 58 which support the seat 57. When the piston 5 arrives at its uppermost position, the compressed air no longer continues to raise said piston, but, as already 115 described, said piston falls by the weight of the parts suspended therefrom, and in succession, the passages 71 for the compressed air are closed, each series of passages 71 being opened at the same time that the series 120 of passages 71 below it is closed. In this manner said series are in succession opened for the passage of compressed air therethrough. When the main piston 5 arrives at the bottom of the cylinder 6, the valve 46 125 is then opened and the process is repeated, as before explained.

The spring 35 is interposed in order to avoid any breakage of the parts owing to imperfect adjustment between the length 130

of the path of the main piston and the total of the lengths of the several paths of the plungers.

95 indicates a spreader for diverting the oil or other liquid being pumped and preventing it escaping by the opening 96 through which the uppermost tube section passes.

An important feature of my invention is that by removing the string of sections and substituting a plunger and stem and connecting the same to the hollow piston stem 4 the pump may be used as a suction pump when desirable to do so.

15 The oblique form of the ports for the escape of the compressed air causes said compressed air to be directed upwardly and outwardly in the pump so as to come in contact with the pump casing. A serious 20 disadvantage in regard to pumping by compressed air is that the compressed air tends to travel faster at the center of the column 25 of fluid within the pump casing, or along the course of least resistance, since the oil or water through friction tends to cling to the surface of the pump casing; therefore 30 the compressed air penetrates the column of oil or water and allows the fluid so penetrated to fall back upon the next following body of fluid greatly decreasing the efficiency of the pump. By directing the compressed air outwardly at suitable intervals, the column of oil or water is better separated 35 into distinct bodies or portions and maintained so separate, and the air cannot escape through the center.

The utility of admitting the air into the pump tube through the openings 71 intermittently, commencing on the upward stroke 40 with the top valve and on the downward stroke with the lower valve is that thereby a reduction is effected in the specific gravity of the column of fluid on the inside of pump tube commencing at the top of column instead 45 of at the base. Said reduction of specific gravity is brought about through the arrangement of valves on the air tube which supplies air to the main lower valve. These valves are so constructed and arranged that 50 they, on the upward stroke of air tube, allow air to pass into the pump tube at different intervals intermittently, commencing at the top of the column of fluid. The advantage of this arrangement is that, instead of 55 the air that passes out of the main lower valve having to work against a pressure generated by an unbroken column of fluid, it works against a column already made lighter, and put into an upward motion 60 through the displacement of fluid in pump tube at intervals with air commencing at the top. This air is also caused (owing to the shape of the openings 77 and 80 through which it is forced) to give the fluid an upward 65 impulse.

I claim:—

1. A compressed air pump comprising a pump tube, a tube in said pump tube, for compressed air, a series of valve-controlled devices carried by said latter tube at intervals therealong for discharging compressed air into said pump tube, and means for automatically opening said devices in succession while maintaining the others closed, substantially as described. 70

2. A compressed air pump comprising a pump tube, a tube in said pump tube, for compressed air, a series of valve-controlled devices carried by said latter tube at intervals therealong for discharging compressed air into said pump tube, a device for discharging compressed air from the bottom of said compressed air tube into said pump tube, and means for automatically opening said devices in succession while maintaining 85 the others closed, substantially as described. 80

3. A compressed air pump comprising a pump tube, a tube in said pump tube for compressed air, a series of valve-controlled devices carried by said latter tube at intervals therealong for discharging compressed air into said pump tube, and means operated by the pressure of compressed air for automatically opening each of said devices 95 in succession, and closing the last device which has been opened, substantially as described. 90

4. A compressed air pump comprising a pump tube, a tube in said pump tube for compressed air, a series of valve-controlled devices carried by said latter tube at intervals therealong for discharging compressed air into said pump tube, and means operated by the pressure of compressed air for 100 automatically opening each of said devices in succession, in an upwardly and downwardly direction alternately, and closing the last device which has been opened, substantially as described. 105

5. A compressed air pump comprising a pump tube, a tube in said pump tube for compressed air, a series of valve-controlled devices carried by said latter tube at intervals therealong for discharging compressed air into said pump tube, a device for discharging compressed air from the bottom of said compressed air tube into said pump tube, and means operated by the pressure of compressed air for automatically opening 115 each of said devices in succession and closing the last device which has been opened, substantially as described. 120

6. A compressed air pump comprising a pump tube, a tube in said pump tube for compressed air, a series of valve-controlled devices carried by said latter tube at intervals therealong for discharging compressed air into said pump tube, a device for discharging compressed air from the bottom 130

of said compressed air tube into said pump tube, and means operated by the pressure of compressed air for automatically opening each of said devices in succession in an upwardly and downwardly direction alternately, and closing the last device which has been opened, substantially as described.

7. A compressed air pump comprising a pump tube, a tube in said pump tube for compressed air, a series of valve-controlled devices carried by said latter tube at intervals therealong for discharging compressed air obliquely upward into said pump tube, and means operated by the pressure of compressed air for automatically opening each of said devices in succession and closing the last device which has been opened, substantially as described.

8. In a compressed air pump, a pump casing, a compressed air conduit arranged centrally in said pump casing, comprising tube sections, means for supporting the lowermost section upon the valve casing, a piston valve secured on the lower end of each tube section, a sleeve secured upon the upper end of each tube section, a conduit in each sleeve

past the valve, and means for automatically reciprocating the conduit through a distance substantially equal to the sum of the paths of the valves, substantially as described.

9. In a compressed air pump, a pump casing, a compressed air conduit arranged centrally in said pump casing, comprising tube sections, means for supporting the lowermost section upon the valve casing, a piston valve secured on the lower end of each tube section, a sleeve secured upon the upper end of each tube section, a conduit in each sleeve past the valve, means for automatically reciprocating the conduit through a distance substantially equal to the sum of the paths of the valve, and a spring interposed between said means and said conduit, substantially as described.

In testimony whereof I have hereunto set my hand in the presence of two subscribing witnesses.

WILLIAM E. STUART.
